(57) **CLAIM**

The ornamental design for a wax melting pot, as shown and described.

DESCRIPTION

FIG. 1 is a top front perspective view of a wax melting pot showing my new design;

FIG. 2 is a bottom front perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a right elevation view thereof; and,

FIG. 8 is a left elevation view thereof.

The evenly dashed broken lines in the drawings depict portions of the wax melting pot that form no part of the claimed design. The long-short-long broken lines indicate boundaries around portions of the wax melting pot that form no part of the claimed design.

1 Claim, 4 Drawing Sheets
